UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,835, dated May 23, 1899.

Application filed April 26, 1899. Serial No. 714,590. Term of patent 14 years.

To all whom it may concern:

Be it known that I, BENJAMIN F. MAYO, a citizen of the United States, residing at Salem, in the county of Essex and Commonwealth of Massachusetts, have invented and produced a new and original Design for a Protective Slug, of which the following is a specification.

Figure 1 is an end view of a protective slug, illustrating my design; and Fig. 2 is an elevation thereof viewed from the open end of the wings.

The leading feature of my design for a protective slug consists of an elongated body transversely bent to present wings extended from a central or connecting portion concavo-convex in shape and uniting said wings.

The protective slug comprises an elongated

body bent transversely at two points, as a b, to leave a central connecting portion c and wings a' b', the central or connecting portion 20 being bent into concavo-convex form.

Having fully described my design, what I claim, and desire to secure by Letters Patent, is—

The design for a protective slug, substantially as herein shown and described.

In testimony whereof I have signed my name to this specification in the presence of two subscribing witnesses.

BENJAMIN F. MAYO.

Witnesses:

GEO. W. GREGORY,
MABEL PARTELOW.
